UNITED STATES PATENT OFFICE.

ARTHUR E. PETERS, OF LITTLETON, COLORADO, ASSIGNOR TO INGERSOLL-RAND COMPANY, OF JERSEY CITY, NEW JERSEY, A CORPORATION OF NEW JERSEY.

DRILL SHARPENER.

Application filed December 17, 1925. Serial No. 76,007.

This invention relates to drill sharpeners, but more particularly to a guiding means for a drill sharpener.

The objects of the invention are to insure alignment of the crosshead with respect to the anvil block, to impart rigidity to sharpeners of this type and to reduce friction between the relatively movable surfaces of the sharpener.

Other objects will be in part obvious and in part pointed out hereinafter.

The invention consists of the combinations of elements, features of construction, and arrangement of parts having the general mode of operation substantially as hereinafter described and more particularly pointed out in the appended claims and illustrated in the accompanying drawings, in which—

Figure 1 is an elevation partly broken away illustrating the manner in which the posts hold the piston and the crosshead in spaced relation with respect to each other,

Figure 2 is an elevation partly broken away showing the manner in which the crosshead is held in alignment with the anvil block, and

Figure 3 is a transverse view taken through Figure 2 on the line 3—3 looking in the direction of the arrows.

Referring to the drawing, the sharpener indicated generally by A is provided with a hollow base B having formed integrally therewith a raising cylinder C. The upper end of the base B is in this instance provided with a lateral flange D which supports an anvil block E. The anvil block E may be secured to the base B in any suitable manner, as for instance by bolts F, and has formed integrally therewith a clamping cylinder G. Within the cylinder G is arranged a reciprocating piston H which carries at its lower side a reduced extension in the form of a piston J which reciprocates within the raising cylinder C.

Secured at one end to the piston H in any suitable manner are a pair of main posts K located on a diameter extending through the longitudinal axis of the machine. These posts extend slidably through sleeves L fitted in the anvil block E and support at their outer ends a cross head O. The inner ends or heads G' of the posts abut the piston H and are located as shown within the clamping cylinder G. The outer ends of the posts K are preferably screw thread-

ed as at P to receive suitable nuts Q whereby the cross head O is clamped securely against shoulders R on the posts K. By this construction the nuts Z are accessible and the heads of the posts K, which do not need to be adjusted may be located in the less readily accessible portion of the machine.

The admission of pressure fluid to the raising cylinder C and the clamping cylinder G is preferably controlled by a common controlling means such as that disclosed in U. S. Patent No. 1,501,918 for sharpener for drill steels, granted July 22, 1924, to myself and Mortimer S. Parkhill. Accordingly, a valve chest S is secured to the side of the anvil block E. Within the valve chest S is arranged a suitable valve (not shown) operatively connected with a lever T whereby the valve may be manually actuated for controlling the admission of pressure fluid to the cylinders and the exhaust of pressure fluid therefrom in the manner described in the aforesaid patent.

In adjacent faces U and V of the anvil block E and the cross head O respectively are formed recesses or sockets W and X for the reception of forming dies Y and Z. The forming dies Y and Z illustrated in the drawings are in this instance adapted for forming the flared portion or bit end of a drill steel and are held in interlocking engagement with the anvil block and the cross head by means of bolts b. The sockets W and X are preferably formed intermediate the ends of the faces U and V. If desired, additional sockets may be formed in the faces U and V, as for instance sockets c and d formed near corresponding ends of the anvil block E and the cross head O respectively for the reception of the shearing knives e and f, or for other similar devices.

Means are provided for forming the cutting bit on drill steels after the flared bit end has been formed on the steel. To this end a cylinder g is preferably secured on one side of the anvil block E at right angles to the diametric line of the main posts and coaxially with the die Y. The cylinder g is provided with a suitable hammer piston (not shown) adapted to deliver blows on a forming dolly h supported by a front head i and extends into the cylinder g to receive the blows of the hammer piston in said cylinder.

In accordance with the present invention, a pair of holes *k* are formed in the anvil block *E* and preferably on corresponding sides of the posts *K* and in line therewith and substantially at right angles to the diameter on which the posts *K* are located. Within the holes *k* are arranged guiding columns *o* provided with annular grooves *p* on that portion which extends into the holes *k*. Pins *q* in this instance extend transversely through the anvil block *E* and cooperate with the annular grooves *p* for preventing endwise movement of said columns. The said guiding columns *o* are supported in the anvil block at that side of the anvil block adjacent the dollying device and located on lines passing through the axes of the main posts, so that the guiding columns are substantially between the main posts and the dollying device.

Formed in the cross head *O* are bores *r* coaxial with the holes *k* in the anvil block *E* and preferably provided with bushings *s* to receive slidably the free ends of the columns *o*.

The guide columns *o* are of sufficient cross sectional area to withstand any side thrust which may occur during the operation of the sharpener. By means of these columns, the cross head *O* will at all times be held in alignment with the anvil block *E* and the posts *K* will at all times be protected against undue strains to which they would ordinarily be subjected when the cross head *O* descends on the article being formed.

Heretofore, in machines of this type, continued side thrust to which the posts *K*, or their equivalent, are constantly subjected, caused considerable wear on the posts and on the parts through which they reciprocate. Such side thrust is, of course, more severe when the machine is being used for forming or sharpening than when it is used merely as a vise for clamping the drill steel during the sharpening operation. Owing to the wear thus caused on the reciprocatory parts of the machine, the cross head at times tends to tilt somewhat, thus making it difficult to properly form the drill steel or other article. By means of the present invention, however, such side thrust against the posts is greatly minimized, the posts and cooperative parts will be protected against wear, and in consequence will render satisfactory service for a considerably longer period of time than will similar parts in machines unprovided with this feature.

I claim:

1. In a drill sharpener, the combination of a clamping cylinder, a piston reciprocating in said cylinder, a stationary anvil block, two posts secured to the piston and located on a diameter extending through the longi-

tudinal axis of the machine, a movable cross head carried by said posts, two guiding columns for the cross head supported in the anvil block at one side of the posts, one column opposite each post, and said columns being located on lines substantially at right angles to the diameter on which the posts are located, and recesses in the anvil block and cross head located between the posts and guiding columns for holding dies, whereby the cross head is held in alignment with the anvil block and side thrust and tilting of the cross head under impact is prevented.

2. In a drill sharpener, the combination of a clamping cylinder, a piston to reciprocate in said cylinder, an anvil block integral with the cylinder and forming a head for one end of the cylinder, a cross head, a pair of posts for holding the cross head and the piston in spaced relation with respect to each other, said posts being slidable through the anvil block, a pair of guide columns seated at one end in the anvil block and extending slidably through the cross head for insuring alignment of the cross head with the anvil block, recesses in the anvil block and cross head located between the posts and guiding columns for holding dies, and pins through the anvil block to cooperate with the guide columns for holding said columns against endwise movement.

3. In a drill sharpener, the combination of a base having a flange, a raising cylinder integral with said base, an anvil block having a clamping cylinder supported on said flange, a piston in said clamping cylinder having a reduced extension in said raising cylinder, a movable cross head above said anvil block, two main posts having their lower ends secured to the clamping piston and passing through the anvil block, the upper ends being secured to the cross head, said posts being located on a diameter extending through the longitudinal axis of the machine, a dollying device mounted at right angles to the diametric line of the said main posts, two guiding columns for the cross head supported in the anvil block at that side of the anvil block adjacent the dollying device and located on lines substantially at right angles to the diametric lines passing through the axes of the main posts, and recesses in the anvil block and cross head located between the posts and guiding columns for holding dies, whereby the cross head is held in alignment with the anvil block and side thrust and tilting of the cross head under impact of the forging operations is prevented.

In testimony whereof I have signed this specification.

ARTHUR E. PETERS.
